UNITED STATES PATENT OFFICE.

OTTO BANNER, OF EASTON, PENNSYLVANIA, ASSIGNOR TO INGERSOLL-RAND COMPANY, OF NEW YORK, N. Y., A CORPORATION OF NEW JERSEY.

TURBINE.

1,090,442.

Specification of Letters Patent. Patented Mar. 17, 1914.

Application filed December 27, 1911. Serial No. 668,034.

To all whom it may concern:

Be it known that I, OTTO BANNER, a subject of the German Emperor, and resident of Easton, in the county of Northampton and 5 State of Pennsylvania, have invented a new and useful Improvement in Turbine-Engines, of which the following is a specification.

This invention consists of a double flow 10 mixed pressure turbine engine of the so-called action or velocity type, the parts being so arranged that intermediate high and low pressure inlets and two outlets are provided, the high pressure element being located in 15 the low pressure inlet chamber intermediate the two oppositely arranged low pressure elements.

A practical embodiment of this invention is represented in the accompanying drawings, in which—

Figure 1 is a view of the turbine engine half in side elevation and half in longitudinal central vertical section, a high pressure blade wheel being shown with one row of 25 blades carried thereby, and Fig. 2 is a detail section showing the high pressure blade wheel having two rows of blades carried thereby with an interposed row of fixed blades carried by the casing.

The engine shaft is denoted by 1, the blade wheel of the high pressure element by 2, its blades by 3; the blade wheels of the two low pressure elements by 4 and their rows of 30 blades by 5. The casing is provided at its ends with chambers 6, 7, communicating with the outlets 8, 9. These chambers and outlets are herein shown as provided in end members of the casing divided in a horizontal plane co-incident with the axis of the 35 shaft 1 into upper and lower half sections 10, 11, and 12, 13. Inside of the end members of the casing are located the cylindrical members which are also shown as divided in a horizontal plane co-incident with the 40 axis of the shaft 1 into upper and lower half sections 14, 15, and 16, 17, respectively. A ring member is interposed between the two cylindrical members of the casing, which ring member is also shown as divided in a 45 horizontal plane co-incident with the axis of the shaft 1 into upper and lower half sections 18, 19. It is to be understood that these 50 different members and sections are to be bolted or otherwise secured together to form 55 a rigid whole surrounding the shaft 1.

The blade wheel 2 of the high pressure element is located within the chamber 20 communicating with the lower pressure inlet 21. The motive fluid within this chamber 20 is caused to pass in opposite directions 60 outwardly through the two low pressure elements into the outlet chambers 6, 7.

A high pressure chamber 22 is provided in a connection 23 carried by the upper half section 18 of the intermediate ring member 65 18, 19, which high pressure inlet chamber is provided with a nozzle or nozzles 24 for directing the motive fluid against the row of blades 3 of the high pressure wheel 2. This high pressure motive fluid after exerting its 70 force upon the high pressure wheel mixes with the low pressure motive fluid and passes outwardly in opposite directions through the low pressure elements into the 75 outlet chambers 6 and 7.

In Fig. 2 I have shown the high pressure wheel 2 as provided with two rows of blades 25, 26, and the casing as provided with an interposed single row of fixed blades 27.

The partitions of the low pressure elements are denoted by 28 and their nozzles by 29.

The bearings for the shaft 1 at the opposite ends of the casing are preferably divided in a horizontal plane co-incident with the 85 axis of the shaft 1 to form upper and lower half sections 30, 31, and 32, 33, respectively.

The lower half sections 11 and 13 of the end members of the casing may be provided with brackets 34, 35, for use in supporting 90 the engine.

While I have shown the high pressure blade wheel as having a greater blade diameter than that of the low pressure blade wheels and have shown it as having only a 95 single row of blades, still it is to be understood that I do not wish to limit myself to this construction as the blading of the high pressure wheel may have a diameter equal to or less than the blading of the low pressure wheels and may have any number of rows of blades as may be desired. I have also shown the turbine engine as having four stages upon each side of the motive fluid inlet in the low pressure elements and the 100 wheels as having single rows of blades but the number of stages and the number of rows of blades may be varied as desired without departing from the scope of my invention.

It will be seen that in an engine of the 110

character herein shown and described, the shaft may be driven either by the high pressure alone or by the low pressure or by a combination of the two according to the work required.

5 What I claim is:—

- 10 1. A mixed pressure turbine engine including a casing divided transversely vertically into end members containing the outlet chambers for the low pressure elements, cylindrical members containing the low pressure elements, and an intermediate ring member containing the high pressure element and low pressure inlet chamber.
- 15 2. A mixed pressure turbine engine including a casing divided horizontally into

upper and lower half sections and transversely vertically into end members containing the outlet chamber for the low pressure elements, cylindrical members containing the low pressure elements and an intermediate ring member containing the high pressure element and low pressure inlet chamber.

In testimony, that I claim the foregoing 25 as my invention, I have signed my name in presence of two witnesses, this 23d day of Dec. 1911.

OTTO BANNER.
